COMBINED MIRROR AND SHELF FOR TOILET ARTICLES

Jack R. Findlay, 3534 Lathrop Ave.,
Santa Susana, Calif. 93063

Filed May 8, 1968, Ser. No. 11,844

Term of patent 14 years

Int. Cl. D6—01

U.S. Cl. D33—26

I claim:

The ornamental design for a combined mirror and shelf for toilet articles, substantially as shown.
